UNITED STATES PATENT OFFICE.

JAMES HOWARD HUFF, OF ROANOKE, VIRGINIA.

WATER-SHIELD FOR AUTOMOBILE-ENGINES.

1,232,550.

Specification of Letters Patent. Patented July 10, 1917.

Application filed November 2, 1916. Serial No. 129,228.

To all whom it may concern:

Be it known that I, JAMES H. HUFF, a citizen of the United States, residing at Roanoke, in the county of Roanoke and State of Virginia, have invented certain new and useful Improvements in Water-Shields for Automobile-Engines, of which the following is a specification.

The present invention relates to means for protecting the engine and associated electrical parts of an automobile from leakage through the hood or cowl that covers the same. As is well known, it is the common practice to employ hoods composed of hingedly connected sections, one of the joints between the sections being located directly above the engine. These joints ordinarily are not water-tight, and consequently leakage sometimes occurs, the water falling upon the engine and causing short circuits.

The primary object of the present invention is to provide a simple and effective means which will prevent this trouble.

25 In the accompanying drawings:—

Figure 1 is a vertical sectional view through the front portion of an automobile, and through the hood, showing the engine in elevation, the hood in section, and the 30 novel shield in place.

Fig. 2 is a cross sectional view substantially on the line 2—2 of Fig. 1.

Fig. 3 is a detail sectional view on the line 3—3 of Fig. 1.

35 Fig. 4 is a perspective view of the shield, and

Fig. 5 is a detail view of the packing strip between the dash and the body of the car.

40 Similar reference numerals designate corresponding parts in all the figures of the drawings.

In the embodiment illustrated, a combustion engine 6 is disclosed, which may be of any desired type, this engine being located in rear of the usual radiator 7 and in front of the dash 8. The dash and radiator are connected by the usual brace rod 9 located above the engine. Covering the engine is 45 the hood, which may be of any desired formation, but in the embodiment disclosed consists of hingedly connected sections 10, one of the hinge joints 11 of which is located centrally over the engine 6.

50 As is well understood by those acquainted

with these structures, this central hinge joint 11 is ordinarily not water-proof, and in case of stormy weather, it sometimes happens that the water leaking therethrough will fall upon the engine in sufficient quantity to short circuit the spark plugs. To prevent this, there is disclosed in the present embodiment, a shield in the form of a double gutter. This shield preferably consists of a single piece of sheet metal having a central longitudinal loop portion 12 that is arranged to snugly embrace the brace rod 9. Extending from opposite sides of this loop portion are wing portions 13 that taper toward their rear ends, and are 60 outwardly and forwardly inclined. The margins of these wing portions are upturned, as illustrated at 14, and thus produce a pair of gutters on opposite sides of the said loop portion 12. As shown particularly in Fig. 1, this shield or gutter structure is sufficiently long to cover the engine and extend beyond the front end of the same, and by mounting it on the brace 65 rod 9, it will be seen that it is disposed 70 directly beneath the central hinge joint 11. Consequently any water passing through the hinge joint will fall upon the shield and be directed by the gutter portions beyond the engine. To maintain the shield 75 in place, it may be secured by clamping bolts 15 passing through openings 16 formed in the upper portions of the wings 13, these bolts serving to grip the loop portion 12 tightly upon the brace rod 9. 80

It will be evident that this device being an element separate from the hood and the rest of the mechanism, may be in the form of an attachment; can be manufactured separately; and applied to the automobile. 85

In order to further secure protection for the electrical mechanism, a packing strip 17 may be interposed between the dash 8 and the body of the car, the same being clamped tightly between the two and thus more effectively preventing the entrance of liquid through the joint and to the coil box, usually mounted on the dash. 90

From the foregoing, it is thought that the 95 construction, operation and many advantages of the herein described invention will be apparent to those skilled in the art, without further description, and it will be understood that various changes in the size, shape, proportion and minor details of con- 100

105

110

struction may be resorted to without departing from the spirit or sacrificing any of the advantages of the invention.

Having thus fully described my invention, 5 what I claim as new, and desire to secure by Letters Patent, is:—

1. The combination with an engine, of a hood covering the same, and a gutter interposed between the hood and engine and having upstanding liquid confining walls and 10 delivering the liquid from one end.

2. The combination with an engine, of a hood covering the same and comprising hingedly connected sections having a joint 15 located over the engine, and a gutter interposed between the hood and engine and located beneath the hood joint, said gutter having upstanding liquid confining walls and an open delivery end.

20 3. The combination with a radiator, a dash, an engine between the two, and a brace connection between the radiator and dash, of an inclined gutter mounted on the brace over the engine, and having upstanding confining walls and an open front end delivery 25 in advance of the engine.

4. The combination with a radiator, a dash, an engine between the two, and a brace rod connecting the radiator and dash, of a 30 water shield for the engine mounted on the brace rod and astride the same, and comprising sloping wing gutters inclined toward one end of the engine, and having upstanding outer side walls.

35 5. An attachment for automobile engines, comprising a water shield having a portion for embracing the brace rod of the radiator, and gutter portions formed on op-

posite sides of the embracing portion provided with upstanding outer side walls and 40 liquid discharge ends.

6. An attachment for automobile engines, 45 formed of sheet metal having an intermediate longitudinal loop portion for embracing the brace rod of a radiator, and forwardly and downwardly inclined gutter portions formed on opposite sides of the loop portion, the marginal portions of the sheet metal being upturned to provide confining walls. 50

7. An attachment for automobile engines formed of sheet metal, comprising a portion for engaging the brace rod of a radiator, 55 said sheet metal being bent to form a longitudinal trough for catching the drip through the joint of the automobile hood and delivering the same beyond the engine, and means for clamping the said portion to the brace rod to support said trough.

8. An attachment for automobile engines 60 formed of sheet metal, comprising a loop portion for embracing the brace rod of an automobile radiator, the portions on opposite sides of said loop portion being formed into longitudinal troughs that decline toward one end, and means for constricting the loop portion about the brace rod to clamp the attachment thereto and support the same over the engine. 65

In testimony whereof I affix my signature 70 in the presence of two witnesses.

JAMES HOWARD HUFF.
